[57] **CLAIM**

The ornamental design for a geodesic dome building, as shown and described.

DESCRIPTION

FIG. 1 is a front elevational view of a geodesic dome building showing my new design;

FIG. 2 is a rear elevational view thereof;

FIG. 3 is a top view showing the roof thereof and some of the shingles which cover the entire roof except for the five seven-sided openings structures in the roof; and

FIG. 4 is a bottom view of my design.

FIG. 1FIG. 2FIG. 3FIG. 4
